PRESSURE GAUGE

Earl Donald Zuck, Quakertown, Pa., assignor to
Ametek, Inc., New York, N.Y.

Filed Feb. 18, 1971, Ser. No. 116,738

Term of patent 14 years

Int. Cl. D10—04

U.S. Cl. D52—6

FIG. 1

FIG. 2

FIG. 3

FIG. 4

FIG. 5

FIG. 6

FIG. 1 is a front elevational view of a pressure gauge showing my new design;

FIG. 2 is a right side elevational view thereof, the left side being a mirror image thereof;

FIG. 3 is a rear elevational view thereof, the lower threaded portions being omitted for ease of illustration;

FIG. 4 is a front elevational view of another form of my new design, wherein the knurled dial cover edge has been omitted and two ribbed sections added to the main housing;

FIG. 5 is a right side elevational view thereof, the left side being a mirror image thereof; and

FIG. 6 is a rear elevational view thereof, the lower threaded portions being omitted for ease of illustration.

I claim:

The ornamental design for a pressure gauge, substantially as shown and described.
